UNITED STATES PATENT OFFICE

LOUIS JEAN CLAIRIS, OF PARIS, FRANCE, ASSIGNOR TO THE TABULATING MACHINE COMPANY, OF ENDICOTT, NEW YORK, A CORPORATION OF NEW JERSEY

COUNTER CUT-OUT

Application filed June 21, 1926. Serial No. 117,368.

This invention relates to tabulating machines and more particularly to counter control circuits and mechanism therefor.

In tabulating machines at present employed it is customary to provide a record card having perforations in columns to indicate various items and data with which it is desired to control the machine. The card is divided into a plurality of groups of columns in order that various data corresponding to a certain item may be simultaneously entered and printed, if a printing device is employed, in different columns on the record sheet. In case a number to be entered into a particular group of columns contains a smaller number of digits than the number of columns set aside for that entry, certain of the columns will remain unpunched and the card area represented thereby is in that particular case unproductive. However, if means is provided for rendering inoperative a certain portion of an accumulator bank when the columns normally controlling that bank are left blank on a particular card, those card columns may be used for operating other devices with a consequent saving in card surface.

It is an object of this invention to provide means for rendering inoperative a portion of an accumulator bank during the passage of a single card.

Another object is to provide means for splitting an accumulator bank whereby a portion thereof only is operative to receive items from a record.

A further object is to provide means for permitting the use of a record card to indicate a greater number of items than that ordinarily represented by the total number of columns thereon.

The above objects, and others which will be apparent as the nature of the invention is disclosed, are accomplished in accordance with the present invention by splitting the common return connection to the accumulator bank, connecting one portion permanently to the line and connecting the other portion to the line through a contact which is controlled by a relay coil included in circuit with one of the card reading brushes.

Means is provided for energizing the relay coil whenever a perforation appears in a certain index position of the selected column and, when energized, the contact completing the circuit to the second portion of the accumulator bank is broken. After the contact has been broken means is provided for preventing it from being closed before the completion of a card cycle.

Although the novel features which are believed to be characteristic of this invention have been pointed out with particularity in the claims appended hereto, the invention itself as to its objects and advantages, the manner of its organization and the mode of its operation may be better understood by referring to the following description taken in connection with the accompanying drawings forming a part thereof in which,

Fig. 1 is a circuit diagram for a printing tabulator constructed in accordance with this invention.

Figs. 2 and 3 illustrate portions of a record card used for controlling the tabulator.

Fig. 4 is a plan view partly in section of a portion of an accumulator bank to which this invention is applied, and

Fig. 5 is an enlarged detail view of one portion of an accumulator bank.

Referring to Fig. 1, a motor TM is employed for driving a printing tabulator during tabulating and listing. This motor is controlled by a series of relays and contacts 10. A reset motor RM is provided for driving the tabulator during the totaling and reset operations at which time a circuit is completed to the motor through a series of contacts and relays 11. The various details of the motors and the motor control circuits are disclosed and described in a copending application of C. D. Lake Serial Number 639,153 filed May 15, 1923, and form no part of the present invention.

The operation of the machine is controlled by perforated record cards which are passed successively between upper brushes 12 and lower brushes 13. Group indicator bank G1 and group control contacts GC may be connected in circuit with these brushes, or any particular selected brushes, by means of plug 100

connections in a manner well known in the art. Brushes 13 are adapted to be plug connected to a bank of counter coils 14 by means of which accumulators 15 are operated and to a bank of printer magnets 16 to which a circuit is completed in the usual manner during listing and total printing.

The common return for the printing and counting magnets is divided into two parts, 10 the circuit to a portion of the bank being completed through bus bar 20 connected permanently to one side of the main supply line 21, and the circuit to the other portion being completed from bus bar 22 to line 21 15 through relay contact 23. Whenever contact 23 is closed the entire tabulating and printing bank is in operative condition ready to receive items from the perforated index card. However, when contact 23 is open, 20 a portion only, in this case one-half, of the tabulating bank is in operative condition. Any perforations occurring in the index point columns normally operating the other portion of this bank will then be of no effect. 25 The perforations in those columns may therefore be employed to represent a different set of items and used to control other mechanism.

A circuit is completed to relay coil 24, 30 which is adapted to operate contacts 23, from line 21 to jack 25 which may be plugged to any desired brush, cam operated contact 26, card lever 27, cam contact 28 and contacts 29 to the other side of the main line 30. Cam 35 contacts 26 are designed to close at a time corresponding to a particular index point position on the record card. If at that time brush 12 senses a hole in the record card the circuit above traced will be completed to 40 relay 24 which will be energized and contact 23 broken. Although cam contacts 26 may be adjusted to complete the circuit at any desired index point position it is desirable to choose an index point position lying 45 outside of the usual range perforated on the card to indicate data to be entered. On a well known type of Hollerith card extra positions called the 11 and 12 or X and Y positions are provided at the top of the card. 50 Consequently a perforation in one of those two positions may be employed to effect the counter control. Cam contact 31 opens when contact 26 is closed and prevents a short-circuit between the two sides of the line. When 55 contact 26 is open contact 31 is closed to complete the circuit to brushes 12 in the usual manner.

When a hole has been encountered in the control position by upper brush 12, relay 24 60 is energized and contact 23 broken, means must now be provided for holding contact 23 open while the card is passing lower brushes 13 and data is being entered into the counter mechanism. One kind of holding device 65 which may be employed and which has been

illustrated herein is controlled by reset bar 32 which is moved once per card cycle to release the clutches to the index wheels of accumulators 15. Reset bar 32 and the armature of relay 24, carrying one of contacts 70 23, are so interrelated mechanically that the armature can be only moved when reset bar 32 has been operated to release the accumulator clutches.

The accumulator clutches are normally released after the entire card field has passed the sensing brushes and the amounts indicated thereon have been entered in the counting wheels. This normally occurs when the sensing brushes are at the 12 position on a 75 Hollerith card. Inasmuch as cards are passing the upper and lower brushes in synchronism the 12 position of a record card will traverse upper brushes 12 at the time the preceding card is occupying a corresponding position under brushes 13 and the counter wheels which have entered the data contained on the preceding card are being released. If at that time a perforation occurs at the 12 position on the card passing the upper brushes, reset bar 32 being depressed, relay 24 is energized and contact 23 broken. As reset bar 32 re-assumes its normal position contact 23 is held open while that record card is passing the lower brushes, the contact being closed at the next reset operation after the card has completely traversed the lower brushes provided a controlling perforation is not present in the following record card.

The details of construction of reset bar 32, relay 24 and contacts 23 are shown in Figs. 4 and 5. Referring to those figures clutches 35 controlling counter wheels 36 are released by bars 37 pivoted on reset bar 32 in a manner well known in the art. For a more detailed description of the particular structure and mechanism for operating the reset bar and its associated clutches reference may be made to the United States Patent to Lake No. 1,307,740, dated June 24, 1919. Bent arm 40 is 100 rigidly attached to reset bar 32 and moves in conjunction therewith. This arm is positioned to cooperate with an insulating section 41 carried by the armature of magnet 24 and movable in connection therewith. Arm 40 prevents movement of the above armature except when reset bar 32 is moved to the left which occurs during the reset operation once per card cycle as heretofore explained. If a circuit is completed through magnet 24 at a 105 time when the perforations on a record card are being sensed by brushes 13 to enter corresponding amounts in an accumulator bank, the armature is prevented from movement and contacts 23 held in a closed position thereby assuring that the operation of the complete bank will not be interrupted until the card cycle has been completed. In a similar manner if contacts 23 are opened at the beginning 110 of a card cycle they are retained open until 115 120 125 130

the end of that cycle when bar 32 is moved to the left and the armature of magnet 24 released by arm 40 becoming disengaged with insulating section 41.

5 Figs. 2 and 3 illustrate sections of a record card showing the saving in space that may be effected by employing the present invention. The record card illustrated in Fig. 2 has a field of eight columns set aside to print an 10 item in this case entitled amount. In case only the right hand four of those columns are employed the left hand portion of the field would remain blank. The card shown in Fig. 3 utilized the four left hand columns which 15 would otherwise be left blank for the purpose of indicating other data. Perforation 45 in the 12 position on this card serves to control the relay circuit heretofore described and disconnects the portion of the accumulator bank 20 normally cooperating with these four columns on the record card whereby the perforations made therein do not affect the accumulator bank used for indicating the amount. The cards which utilize only four columns 25 for the amount may then be sorted out from the rest and other accounting operations dealing with the number columns can be performed on these cards.

Although this invention has been shown as 30 applied to particular apparatus operated in a specific manner, it is not to be limited thereto but only in accordance with the scope of the following claims.

What I claim is:

35 1. In an accounting machine, a bank of accumulator elements, a plurality of sets of sensing brushes for deriving data from record cards, and means controlled by a particular brush of one set for rendering inoperative a portion of said other set during the 40 passage of a record card.

2. An accounting machine normally controlled by perforated record cards, a plurality of sets of brushes for sensing the data 45 entered upon said cards, an accumulator bank, means connecting said bank with one of said sets of brushes and means for disconnecting a portion of said bank from said brushes, said last mentioned means being controlled 50 by one of said second sets of brushes.

3. In an accounting machine controlled by perforated record cards, a plurality of sets of sensing brushes for deriving data therefrom, an accumulator bank, means for connecting said bank with one of said sets of brushes, and a relay for rendering inoperative, a portion of said bank said relay being controlled by said second set of brushes in 55 response to a perforation in a particular index point position on said record card.

4. In an accounting machine controlled by perforated record cards, a plurality of sets of sensing brushes for deriving data therefrom, an accumulator bank, means for connecting said bank with one of said sets of

brushes, a relay for rendering inoperative a portion of said bank, said relay being controlled by said second set of brushes in response to a perforation in a particular index point position on said record card, and means 70 for maintaining said portion in inoperative position during a complete card cycle.

5. In an accounting machine operated in response to perforated record cards, a plurality of sets of sensing brushes, a bank of 75 accumulator elements, means for connecting said bank to one of said sets of brushes, means for disconnecting a portion of said bank, comprising a relay and armature, means controlled by said second set of 80 brushes for rendering said relay operative whereby said contact is broken, and means for holding said contact in an open position for the duration of a card cycle.

6. In an accounting machine operated 85 in response to perforated record cards, a plurality of sets of sensing brushes, a bank of accumulator elements, means for connecting said bank to one of said sets of brushes, means for disconnecting a portion of said bank, comprising a relay and armature, means controlled by said second set of 90 brushes for rendering said relay operative whereby said contact is broken, and means for holding said contact in an open 95 position for the duration of a card cycle comprising a detent carried on the reset bar of said accumulator.

7. In an accounting machine operated in response to perforated record cards, a plurality of sets of sensing brushes, a bank of 100 accumulator elements, means for connecting said bank to one of said sets of brushes, means for disconnecting a portion of said bank comprising a contact, a relay and armature associated therewith for controlling said contact, means for associating said relay with any one of said second set of brushes, means for completing the circuit to said relay at a 105 time corresponding to a certain index point position of said record card whereby after a perforation occurs in that position said relay will be energized, a reset bar for releasing the clutches to said accumulator bank once per card cycle and a detent associated 110 with said bar adapted to prevent said armature being moved except when the bar is moved during a resetting operation whereby said contact is held in either open or closed position while said record card is traversing 115 said first mentioned set of brushes.

8. In a tabulating machine controlled by record cards, a plurality of sets of sensing brushes, an accumulator bank, means for connecting one of said sets to said bank and means controlled by said record card while the card is passing one set of brushes for rendering a portion of said accumulator banks inoperative while the cards are passing 120 the other set of brushes.

9. In an accounting machine, a bank of accumulator devices, a plurality of sets of sensing elements for deriving data from record cards to control the accumulator devices, and means controlled by a particular element of one set for rendering inoperative a portion of said other set when the record card is being analyzed.

In testimony whereof I hereto affix my
10 signature.

LOUIS JEAN CLAIRIS.
